[57] CLAIM

The ornamental design for a brake or clutch lever or the like for a motorcycle, as shown and described.

DESCRIPTION

FIG. 1 is a perspective view of a brake or clutch lever or the like for a motorcycle showing my new design, it being understood that the broken lines are for illustrative purposes only and form no part of the claimed design;

FIG. 2 is a top plan view thereof;

FIG. 3 is a left side elevational view thereof;

FIG. 4 is a right side elevational view thereof;

FIG. 5 is a bottom plan view thereof; and,

FIG. 6 is a front elevational view thereof.

FIG. 1**FIG. 2****FIG. 3**

FIG. 4**FIG. 5****FIG. 6**
